SCREW THREADING DIE

Ernest T. Bysshe and Robert R. Finn, Springfield, Vt., assignors to Jones & Lamson Machine Company, Springfield, Vt., a corporation of Vermont

Application August 8, 1932, Serial No. 627,878

17 Claims. (Cl. 10—100)

This invention relates to screw threading dies and more particularly to that type of dies wherein the chasers or thread cutting elements are rockable between closed and opened positions.

One of the objects of this invention is to provide a construction wherein the trunnions and chaser or thread cutting element carriers are mountable so that the individual chasers can be adjusted at the bench.

A further object is to provide a die which can be opened either by hand or automatically.

A further object is to provide for positive opening of the die so that dependence on springs for this purpose will not be necessary.

A still further object is to provide a one piece cam member for moving the thread cutting element holders.

Further objects and advantages will appear from a more complete description of an embodiment of this invention disclosed in the accompanying drawings, of which

Figures 1 and 2 are front end elevations of the die in closed and opened conditions, respectively.

Figure 3 is a side elevation, the die being closed.

Figure 4 is a section on line 4—4 of Figure 1.

Figure 5 is a front elevation of the die, the chaser carriers being removed.

Figure 6 is a detail section on line 6—6 of Figure 4.

Figures 7 and 8 are sections on the correspondingly numbered section lines of Figure 4.

Figures 9 and 10 are sections on the correspondingly numbered section lines of Figure 5.

Figure 11 is a detail section on line 11—11 of Figure 19.

Figure 12 is a fragmentary plan view of the die.

Figure 13 is a perspective of a cam and latch block.

Figure 14 is a fragmentary plan of a portion of the die, the cam and latch block being shown in section.

Figure 15 is a fragmentary perspective of the chaser carrier actuating ring.

Figures 16 and 17 are views similar to Figure 9, but showing the die opened, respectively, by retraction of the releasing sleeve, and by movement of the chasers onto the work while the die holder is held against movement.

Figure 18 is a view similar to Figure 14 but showing the cam block and chaser actuating ring in different relative positions.

Figure 19 is a section on line 19—19 of Figure 4.

Figure 20 is a fragmentary section to a larger

scale showing the adjusting mechanism for determining the limiting positions of the chasers.

Figures 21 and 22 are perspectives of a chaser carrier and chaser.

Figure 23 is a detail section on line 23—23 of Figure 22, the chaser-retaining block being removed.

As shown in the drawings the die comprises a body portion 1 substantially cylindrical in form and having a central axial opening 2 extending therethrough within which the work may extend. This body portion is provided with a plurality of trunnion-receiving bearing openings as at 3 which are arranged in circular series about the axis of the body. As shown, four of these trunnion openings are employed, although more or less might be used as desired. Within each of these trunnion-bearing openings 3 is positioned a trunnion 4 of a thread cutting element carrier 5. These carriers may be constructed as shown particularly in Figures 21, 22 and 23 wherein they are designed to carry tangent type chasers such as 6. The trunnion portion 4 of each carrier is shown integral with a body portion 7 and integral with this body portion is an actuating arm 8. This actuating arm has a rib portion 9 and a web portion 10. The body portion is provided with a dovetail groove 11 for the reception of the correspondingly shaped part of the chaser 6, and a retaining or clamping block 12 provided with a face 13 conforming to one side of the chaser dove-tail may be secured in position as by screws 14 in a suitable seat 15 of the carrier body to secure the chaser in position. These cooperating parts are so formed as to fix the chaser with the ribs 17, at the ends of which the thread cutting edges of the chaser are formed, making the proper helix angle to the axis of the die body when the carriers are in position with their trunnions in the die body trunnion openings 3.

In order to adjust the chasers lengthwise their dovetail faces as shown are provided with spaced notches 18 within which may engage a flange 19 on a collar 20 threaded on a stud 21 projecting from the body of the carrier and spaced from and parallel to the back face of the chaser. The axis of each trunnion 4 passes substantially in the plane of the rib faces of the chaser so that in all angular positions of the carrier these rib faces will be substantially tangential to the work to which they may be presented.

Each of the trunnions, as shown, is provided with a portion 25 of reduced diameter between its ends with which may be engaged a mating flange portion 26 on a retaining ring 27 journaled on the

body portion. This retaining ring is provided with a flange 28 which engages about the end portion 29 of each trunnion inwardly of the reduced diameter portion 25 and abuts against 5 an end face of the die body. The flange portion 26 of the retaining ring, as shown in Figure 8, is provided with cut-outs 30 which are normally out of alignment with the trunnions but which may be positioned opposite thereto by turning the retaining ring away from its normal angular position 10 which is shown in Figure 8. When these cut-outs are in registry with the trunnions the carriers may be removed endwise from the die body 1. The retaining ring may be held against removal 15 from the body portion at its rear end by means of a ring 35 secured in position, as shown best in Figures 11 and 19, as by screws 36 threaded into the rear end face of the die body 1. Journalled on the forward end of the body 1 is a die actuating 20 or cam ring 40 which is provided with cam grooves 41 in its forward face within which engage the ribs 9 on the chaser carriers, these cam grooves being so related to the chaser actuating arms, their sides forming thrust abutments there- 25 for, that rocking of the ring 40 about the axis of the die body simultaneously rocks the carriers between die-closed positions, shown in Figure 1, and die-open positions shown in Figure 2. The carriers are normally urged toward die-open positions 30 as by means of a spring 45 seated in an arcuate channel socket in the body 1 as at 46, one end of the spring 45 reacting against the end of the socket and the other against a pin 47 secured to the ring 40.

35 The carriers may be held in die-closed position, however, as by a latch mechanism. Such a mechanism, as shown herein, comprises a combined latch and cam block 50 shown detached in Figure 13. Two of these combined latch and cam blocks are shown, each being slidably mounted in 40 a slot 51 in an adjusting ring 52. This adjusting ring is journalled on the die body between the actuating ring 40 and the retaining ring 27 and is held from axial movement relative to the die body 45 by reason of its position between the rings 27 and 40. The ring 40 is held on the die body by a shoulder portion 55 of the die body. Each block 50 is provided with a latch face 60 and an inclined cam face 61 which cooperate respectively with a latch face 62 and a cam face 63 in a slot 64 in the rear edge of the actuating ring 40.

When each of the blocks 50 is in its forward position relative to the die body, its latch face 60 is engaged by the latch face 62 of the actuating 55 ring 40, as shown in Figure 14, these latch faces being held in contact by the action of the spring 46, and the ring 52 being held against rotation on the body by means which will be described presently. The actuating ring 40 is thus held 60 in die-closed position. To release the chaser carriers so that they may be moved by the spring to open position it is necessary to first retract the blocks 50 toward the rear face of the die body. This may be accomplished by axial movement 65 of a sleeve 65 which encloses the rear portion of the actuating ring 40 and also encloses the adjusting ring 52 and the trunnion-retaining ring 27. This sleeve 65 is operatively connected to the blocks 50 as by means of bosses 70 such as 66, one of these being shown integral with each of the blocks 50, which is seated in a perforation 67 in the sleeve 65. Thus by moving the sleeve 65 axially of the die and back from its forward face the projections 68 of the 75 blocks 50 on which the latch faces 60 and the

cam faces 61 are formed are moved away from the position shown in Figure 14 toward the position shown in Figure 18. The initial movement of the blocks in this direction frees the actuating ring and permits the spring 46 to rotate the ring 40 to die-open position. Should it for any reason be prevented from moving to this position, further axial movement of the block 50 after the release has been effected brings its inclined cam face 61 against the inclined cam face 63 of the actuating ring 40 and continued axial movement of the sleeve 65 thus acts positively to turn the ring 40 to its released position which is shown in Figure 18. The portion 68 of the block after being moved sufficiently to release the spring substantially fills the width of the slot 64 of the ring so that any rocking motion of the actuating ring is accompanied by an axial motion of the sleeve 65. In order to close the die it is only necessary to push the sleeve 65 forwardly, whereupon engagement of the portion 68 in the slot 64 acts to rotate the actuating ring 40 against the action of the spring 46 until the blocks 50 have been moved forwardly to their latching position. This return of the carriers to die-closed position 100 may also be effected by rocking the ring 40 in die-closing direction to a sufficient extent and this may be done by means of an actuating handle 70 extending therefrom.

In order to determine the limits of rocking motion of the actuating ring 40, thus to determine the limits of die open and closed positions, the ring 52 is made adjustable about the axis of the die. An adjusting means for this purpose is shown in detail in Figure 20. The ring 52 is provided with a hole 75 extending therethrough which at its central portion opens into the interior of the ring. One portion of this hole, as at 76, is threaded and engageable with these threads is the correspondingly threaded portion 110 of a sleeve 77. This sleeve is keyed for rotation to a shaft 78 having at one end a head 79, journalled in the opening 75, and provided with suitable means such as a socket of polygonal cross section as 80 to receive a tool with which it may 115 be turned. The keyed connection of the threaded sleeve 77 to the shaft 78, as shown, comprises a ring 81 having key portions 82 engaging notches 83 in the sleeve 77 and splined onto the end of the shaft 78 to which it is secured by a nut 85 threaded on the reduced portion 86 of the shaft. Between the head 79 and the threaded sleeve 76 is mounted another sleeve 90 within which the shaft 78 is rotatable and which is provided on one side with suitable rack teeth 91 which mesh 120 with pinion teeth 92 cut into the body portion 1, this body portion being relieved at either side of these teeth 92 so as to permit a rocking movement of the adjusting ring 52 thereon. The sleeve 65 is provided with a slot as at 95 of sufficient size to permit a tool to be inserted therethrough and into engagement with the opening 80 in the head 79 so that this adjusting mechanism is accessible for actuation from outside of the die. Similarly the sleeve 65 is provided with a slot 96 in axial alignment with the trunnion-retaining ring 27 when the sleeve 65 is in one of its extreme positions, herein shown as the closed die position, in order that a rod may be inserted through the slot and into a perforation 97 in the periphery of the ring 27 so that this ring may be turned to release the trunnions or to hold them in operative positions as desired.

Means are also provided by which the die may be automatically opened by holding back the ring 150

65 against forward travel with the thread cutting element carriers as they are fed forward by their engagement with the work. To this end the die body is slidably related to a holder 100, which, 5 as shown, is provided with a central opening 101 within which the work may extend and which is provided with a counterbored end portion 102 which is slidable over a rearwardly extended sleeve portion 103 of the die body. This holder 10 has fixed therein the rear ends of headed pins 104, the heads of which ride in openings 105 extended axially through the body 1 intermediate the trunnion bearing openings 3. Two of such openings 105 are shown though more might be 15 used if desired. Between the heads 106 of the pins 104 and the ring 35 secured to the rear face of the body 1 are positioned coil springs 108 which react between the ring 35 and these heads and tend to hold the body retracted relative to the 20 holder in the position shown in Figure 16. The holder 100 has an enlarged end head portion 110 within which the rear ends of the pins 104 are secured as by means of cross pins 111 therein arranged in slots 112 in the head 110 and passing 25 through the pins 104. Dowel pins 114 extending from the holder 100 into holes in the body 1 hold the parts against relative rotation. On the outer face of the head 110 rides the rear extremity of the sleeve 65, forwardly of which it is provided with a peripheral groove 115 with which 30 may engage any suitable type of retaining or actuating fork to prevent the forward travel of the sleeve 65 with the die body when it is desired to cause automatic opening of the die and 35 by actuation of which the die may be opened or closed. Back of the bearing portion of the sleeve 65 on the head 110 this head is shown as provided with an annular abutment 116 which limits the rearward travel of the sleeve 65 thereon to 40 the position shown in Figure 16 wherein the sleeve 65 has been retracted as by hand to die-open position. If, however, the die is in operation and the holder 100 is held against forward feed therewith as the thread cutting elements 45 feed onto the work, the die body is pulled forward therewith onto the work, and an enlarged flange portion 120 on the forward end of the head 110 engages the end wall portion 121 of the sleeve 65, causing this sleeve to be retracted 50 relative to the body, holding it against forward movement with the die body, until the sleeve is in die released or open position, as shown in Figure 17, whereupon the thread cutting elements are entirely freed from the work. The springs 55 108 then force the die body back relative to the holder into the position shown in Figure 16 with the holder flange 120 against the outer face of the retaining ring 35.

It will thus be seen that the die may be closed 60 either by moving the sleeve 65 forwardly, or by rocking the actuating ring, as by means of the handle 70, and that when the die is closed it is held latched in closed position until the sleeve 65 is moved rearwardly relative to the die to an 65 extent sufficiently to release the latch, whereupon further rearward motion of the sleeve 65 acts positively to open the die. Also it will be seen that holding of the sleeve 65, or the holder 100, against forward movement with the die as 70 it is being pulled onto the work by threaded engagement of its cutting elements therewith acts to open the die and thus release it from the work.

From the foregoing description of an embodiment of this invention, which has been shown

by way of illustration, it should be evident that various changes and modifications might be made without departing from the spirit or scope of this invention as defined by the appended claims.

We claim:

1. A die having a body provided with a plurality of trunnion-receiving openings arranged in circular series, a plurality of thread cutting element carriers each having a trunnion journaled in one of said openings, a ring rockable about the axis of said series operatively connected to said carriers to cause rocking of said ring to simultaneously rock said carriers, said carriers having thread-cutting elements having their cutting portions eccentrically disposed to said trunnions and movable toward and from said axis to open or close said die on rocking of said ring in opposite directions, an element for limiting the rocking of said ring, yielding means pressing said ring toward its limited angular position, and means carrying said element for movement axially of said body, said element and ring having cooperating cam faces shaped to cause axial movement of said element in one direction to turn said ring positively in a direction to open the die.
2. A die having a body provided with a plurality of trunnion-receiving openings arranged in circular series, a plurality of thread cutting element carriers each having a trunnion journaled in one of said openings, a ring rockable about the axis of said series operatively connected to said carriers to cause rocking of said ring to simultaneously rock said carriers, said carriers having thread-cutting elements having their cutting portions eccentrically disposed to said trunnions and movable toward and from said axis to open or close said die on rocking of said ring in opposite directions, an element for limiting the rocking of said ring, yielding means pressing said ring toward its limited angular position, means carrying said element for movement axially of said body, said element and ring having cooperating cam faces shaped to cause axial movement of said element in one direction to turn said ring positively in a direction to open the die, and means for adjusting said element angularly about said axis to adjust the limits of rocking of said ring.
3. A die having a body provided with a plurality of trunnion-receiving openings arranged in circular series, a plurality of thread cutting element carriers each having a trunnion journaled in one of said openings, a ring rockable about the axis of said series operatively connected to said carriers to cause rocking of said ring to simultaneously rock said carriers, said carriers having thread-cutting elements having their cutting portions eccentrically disposed to said trunnions and movable toward and from said axis to open or close said die on rocking of said ring in opposite directions, an element for limiting the rocking of said ring, means carrying said element for movement axially of said body, said element and ring having cooperating cam faces shaped to cause axial movement of said element in one direction to turn said ring positively in a direction to open the die after an initial lost motion, means for adjusting said element angularly about said axis to adjust the limits of rocking of said ring and to prevent turning of said ring to open the die when said die is fully closed except after an initial axial movement of said element taking up said lost motion in die-opening direction.
4. A die having a generally cylindrical body

- provided with trunnion journal openings arranged in circular series about its axis, a plurality of thread cutting element carriers each having a trunnion journaled in one of said openings, an actuating ring journaled on said body and operatively connected to said carriers to cause rocking of said ring to rock said carriers to open or close the die, a sleeve slideable axially on said body, a block connected to said sleeve to move therewith and engaging in a slot in said actuating ring angularly related to the axis of said body, whereby axial motion of said sleeve rocks said ring, said block and slot being shaped to afford an initial lost motion of said block toward chaser-open position before such motion is effective to rock said ring, and cooperating during such lost motion to prevent turning of said ring toward die-open position, an adjusting ring journaled on said body and having a guideway for said block axially of said body, and means for adjusting said adjusting ring about the axis of said body.
5. A die having a generally cylindrical body provided with trunnion journal openings arranged in circular series about its axis, a plurality of thread cutting element carriers each having a trunnion journaled in one of said openings, an actuating ring journaled on said body and operatively connected to said carriers to cause rocking of said ring to rock said carriers to open or close the die, a sleeve slideable axially on said body, a block connected to said sleeve to move therewith and engaging in a slot in said actuating ring angularly related to the axis of said body, whereby axial motion of said sleeve rocks said ring, said block and slot being shaped to afford an initial lost motion of said block toward chaser-open position before such motion is effective to rock said ring, and cooperating during such lost motion to prevent turning of said ring toward die-open position, an adjusting ring journaled on said body and having a guideway for said block axially of said body, and means for adjusting said adjusting ring about the axis of said body, said sleeve enclosing said adjusting ring and having an opening through which said adjusting means is accessible for actuation.
6. A die having a generally cylindrical body provided with a plurality of trunnion journal openings arranged in circular series about its axis, a plurality of thread-cutting element carriers each having a trunnion journaled in one of said openings, each of said trunnions having a reduced portion between its ends, a trunnion-retaining ring on said body having parts engageable in said reduced trunnion portions, said part having cut-outs movable by rocking of said retaining ring into registry with said trunnions to permit removal of said carriers, a sleeve movable axially of said body and enclosing said retaining ring and having an opening through which said retaining ring may be accessible for rocking said retaining ring, and operative connections between said sleeve and carriers for causing axial movement of said sleeve to rock said carriers to open and close the die.
7. A die having a generally cylindrical body provided with a plurality of trunnion journal openings arranged in circular series about its axis, a plurality of thread cutting element carriers each having a trunnion journaled in one of said openings, each of said trunnions having a reduced portion between its ends, a trunnion-retaining ring on said body having parts engageable in said reduced trunnion portions, said part having cut-outs movable by rocking of said retaining ring into registry with said trunnions to permit removal of said carriers, a sleeve movable axially of said body and enclosing said retaining ring and having an opening through which said retaining ring may be accessible for rocking said retaining ring, and operative connections between said sleeve and carriers for causing axial movement of said sleeve to rock said carriers to open and close the die.
8. A die having a body, a plurality of thread cutting element carriers pivotally mounted on said body, means for rocking said carriers simultaneously to open or close the die, a spring tending to hold said die open, a latch for holding said die closed, a member movable axially of said body for releasing said latch, and means operatively connecting said member and rocking means acting on continued movement of said member in the same direction after releasing said latch to positively open said die.
9. A die having a body, a plurality of thread cutting element carriers pivotally mounted on said body, means for rocking said carriers simultaneously to open or close the die, a spring tending to hold said die open, a latch for holding said die closed, a member movable axially of said body for releasing said latch, means operatively connecting said member and rocking means acting on continued movement of said member in the same direction after releasing said latch to positively open said die, and means for adjusting said latch angularly about the axis of said body to determine the limit of rocking of said carriers.
10. A die having a body, a plurality of thread-cutting element carriers movably mounted on said body, and carrier-controlling mechanism for simultaneously moving said carriers to open or close the die, said mechanism including a member angularly adjustable about the axis of said body, a threaded socket in said member, an adjusting screw engaging said socket, and operative connections between said screw and body for producing such adjustment.
11. A die having a body, a plurality of thread cutting element carriers movably mounted on said body, and carrier-controlling mechanism for simultaneously moving said carriers to open or close the die, said mechanism including a member angularly adjustable about the axis of said body, a threaded socket in said member, an adjusting screw engaging said socket, and operative connections including meshing rack and pinion teeth between said screw and body for producing such adjustment.
12. A die having a body, a die holder to which said body is slidably connected, means for yieldingly holding said body in one position relative to said holder, a plurality of thread-cutting element carriers movably supported by said body to move between die open and closed positions, spring means tending to hold said carriers in open positions, a latch for holding said carriers in closed positions, means actuated by relative motion of said holder and body from one position to release said latch, and means operatively connected to said carriers acting positively to move said carriers to open positions on further relative motion of said holder and body after releasing said latch.
13. A die having a body, a die holder to which

- 5 said body is slidably connected, means for yieldingly holding said body retracted relative to said holder, a plurality of thread-cutting element carriers movable on said body between die open and closed positions, and a member movable axially of said body operatively related to said carriers to move said carriers to closed position on movement of said member away from said holder and to move said carriers positively to open position on movement of said member in the reverse direction, said member and holder having portions engageable on movement of said body from said holder, as by the cutting elements feeding onto the work while said holder is held against 15 axial movement to positively open said die.
14. A die having a body, a die holder to which said body is slidably connected, means for yieldingly holding said body retracted relative to said holder, a plurality of thread-cutting element carriers movable on said body between die open and closed positions, resilient means yieldingly holding said carriers in die-open position, a latch for holding said carriers in die-closed position, a member movable axially of said body and operative to release said latch on movement toward 25 said holder and having operative connection thereto to positively open said die on further movement in the same direction, and connections between said member and holder for causing advance of said body by feed of the thread-cutting elements onto the work when said holder is held from axial movement to move said member relatively to said body to release said carriers and to open the die.
- 35 15. A die comprising a body, a plurality of thread-cutting element carriers pivotally mounted on said body, a ring rockable on said body and operatively connected to said carriers for simultaneously rocking said carriers to open or 40 close said die, a spring tending to hold said die open, said ring having a slot therein, a block having a latch face on one side and a cam face on the other engageable in said slot and operating with mating faces of said slot, said 45 latch faces being held normally in contact by
- 80 said spring, means for holding said block against rotation about the axis of said ring while permitting axial motion thereof, and means actuatable to move said block axially of said ring to first release said latch faces from each other and then to bring said cam faces into contact if said spring is unable to move said ring to full open position, whereby continued axial movement of said block in the same direction acts to positively move said ring to die-open position.
- 85 16. A die comprising a body portion, a plurality of thread-cutting element carriers pivotally mounted on said body, a ring rockable on said body and operatively connected to said carriers for simultaneously rocking said carriers to open or close said die, a spring tending to hold said die open, said ring having a slot therein, a block having a latch face on one side and a cam face on the other engageable in said slot and cooperating with mating faces of said slot, said 90 latch faces being held normally in contact by said spring, means for holding said block against rotation about the axis of said ring while permitting axial motion thereof, means actuatable to move said block axially of said ring to first release said latch faces from each other and then to bring said cam faces into contact if said spring is unable to move said ring to full open position, whereby continued axial movement of said block in the same direction acts to positively move 95 said ring to die-open position, and means for adjusting said block-holding means angularly about the axis of said ring.
- 100 17. A die comprising a body, thread cutting elements rockably carried by said body to move thereon between die-closed and die-open positions, resilient means for rocking said elements to die-open position, a latch member for holding said elements in die-closed position, and operative connections between said latch member and 105 said elements positively moving said elements to die-open position on continued movement of said latch after it has released said elements.
